UNITED STATES PATENT OFFICE.

ISAAC JONES, OF DENVER, COLORADO.

COMBINED FLASH LIGHT AND HANDLE.

Application filed March 6, 1924. Serial No. 697,245.

This invention embodies improvements in combined flashlights and handles.

While the invention is not to be restricted to any particular field or spheres of usefulness, it may be said to have been more especially devised as a railroad lamp, in avoidance of the obviously unsatisfactory oil lamps heretofore generally employed, for car and equipment and analogous inspecting, checking, repair work and other railroad or like uses, and for many other varied purposes, such as a household, factory, shop or analogous accessory, an accessory for garages and other places, especially if they store oils or other high inflammables or explosives, a trouble light and handy accessory for motorists, an accessory for tourist, camping and outing trips, and in short for the uses of a general utility light.

One object of the invention has been to provide such a type of light which, in addition to its being adapted for facile manual manipulations, may be so conveniently hung from a belt, trouser band, garment pocket or other appropriate part of the apparel of the user, as to properly direct or focus the light on the work to be done, while at the same time leaving both hands entirely unhampered in the accomplishment thereof. Another and an analogous object and advantage is to permit of its suspension from almost any form of rail, board, hook, rod, bar or iron, at any desired angle and whether even upside down or otherwise as distinguished from the impossible use of oil lamps, as well as to allow for its tilted mounting upon a substantially flat-surfaced body, the ground or other like support, conveniently at hand, with the said light properly directed or focused upon the work or other material object as desired.

The foregoing as well as other objects and advantages, however, including simplicity, maximum durability and efficiency in operation, with a minimum number of parts little liable to get out of order, compactness in combined structure, and comparatively small costs of production and assembly, will be so clearly apparent as incidental to the following disclosure, it is believed, that it would serve no useful purpose now to further enlarge upon the same. With these prefacing remarks, therefore, reference will be immediately had to the accompanying drawings, illustrating a practical embodiment of the improvements, in which drawings

Figure 1 is a longitudinal sectional view through the casing, lens and reflector of the light, taken on the line 1—1 of Fig. 2, with the battery shown in elevation and partly broken away, and an adjustable handle shown at two positions in dotted lines; Figure 2 is a view, partly in longitudinal section and elevation, looking towards the right of Fig. 1; Figure 3 is a top plan view; Figure 4 is a cross-sectional view taken along the line 4—4 of Fig. 2; Figure 5 is a cross-sectional view on the line 5—5 of Fig. 1; and Figure 6 is an elevational view, drawn on a reduced scale, showing the lamp 70 tiltingly mounted in one position on a flat-surfaced or analogous support.

10 designates a casing, which may be cylindrical as shown, for housing a battery 11 and a curved reflector or parabola 12 that 75 axially receives and supports an electric lamp 13.

The battery is provided with the electrode terminal spring contact arms 14 and 15 at one end thereof, the element 14 projecting 80 centrally over the battery end, while the other element 15 is disposed angularly thereto towards the peripheral face of the battery, the other end of the battery being preferably supported by an outwardly tensioned coiled 85 or other spring 16, for obvious reasons.

The casing 10 may be provided with an internal longitudinally disposed trough-like or other suitable guiding and retaining means 17 for the battery 11, receiving a corner 90 edge face of the battery if squared, to maintain the terminal contact arms 14 and 15 properly positioned relatively to the contact terminals of the lamp 13, but of course the battery could be of any suitable shape and 95 held positioned in any other suitable way.

The insulated base contact 18 of the lamp engages the contact arm 14, while the central portion of the reflector 12 may have a boss, through which the lamp base is threaded, and this boss is snugly encompassed by and in electrical connection with a suitable radially disposed spring contact arm or member 20, the outer end of which may be in the nature of a shorter or longer segmental portion, than as actually shown by its T-like head construction, that is adapted to engage the contact arm 15.

In the construction as actually illustrated, although the manner of making and breaking the electrical circuit could be otherwise provided for if desired, the reflector 12 is

mounted to be rotatably oscillated, and of course the contact arm 20 is so fixed thereto as to be turned therewith, for opening and closing the electrical circuit.

5 To this end, the reflector is provided with an outwardly projected annular flange 21 which seats along its inner face upon the edge face of the casing 10, while its outside face seats a lens 22, contained within a capping rim 23. The said capping rim rotatably fits the outer open end of the casing 10, and is provided with an inturned seating flange 24 for receiving and clamping a retaining ring 25 against the lens 22. Although additional securing means between the necessary parts could be effected, this assembly of itself is such that when the rim 23 is slightly turned, one way or the other, the other parts move in unison therewith, 15 that is to say that the contact arm 20 is swung into or out of contact relation with the contact arm 15, as the case might be, with the contact 18 in engagement with the other spring arm 14.

20 25 For conveniently and detachably connecting this capping rim 23, in rotatable association with the casing end, the wall of the latter is peripherally slotted, as at 26 and 27, say from diametric positions, to receive the inturned ends or terminals 28 and 29 of an arcuate resilient member 30, which is affixed centrally to the outside face of the rim 23, and which said inturned ends 28-29 are adapted to be projected through complementary apertures, in the rim 23, registering with said slots 28-29. It will also be seen that the resilient arcuate element 30 is so tensioned that its ends normally spring outwardly, as shown in dotted lines at Fig. 5, but when the capping rim is applied to the casing and the inturned ends 28-29 sprung inwardly through said apertures, then these ends are held clasped to the capping rim and rotatable therewith along said slots, while functioning as retaining means for said capping rim against endwise displacement, the ends of said slots serving as limiting means to the degree of rotation in either direction.

30 35 40 45 50 It will be seen, therefore, that I have produced an extremely neat, durable, conveniently compact and safe portable electric lamp, the opening and closing of the electric circuit of which may be controlled simply by slight reverse turns of the capping rim thereof, and which embodies a reflector element, for properly directing the rays of light, a feature in itself not common to the ordinary lamp or lantern such as used by railroad workers, auto-mechanics or garage men.

55 60 65 More important than the foregoing, however, is the feature of a certain adjustable form of handle that is novelly mounted as combined with the lamp casing, which

handle as a unitary structure functions as a hand grip, a clip or clasp member, a hanger element, or other form of supporting means for the lamp proper, being rotatably associated with the lamp casing in such a manner as to be maintained rigidly fixed at all times against displacement other than its rotary adjustment relatively to the lamp casing.

The handle could be of other shapes than 75 as actually illustrated, but it is shown somewhat like a double U-member, embodying a shorter arm 31 joined by an intermediate curving end portion 33 with a longer arm 32, the said longer arm being opposed to the 80 said shorter arm, in substantially parallel spaced relation, and terminating at its free end in an open hook 34, the extremity of which latter is substantially spaced from the end of the short arm 31. The hook 34 is 85 shown as being turned inwardly, but it could be projected outwardly, or in fact there could be two such hooks, if desired, one disposed inwardly and the other outwardly.

90 The long arm 32 of the handle may preferably be provided with a plural key-hole slot, or its equivalent, shown as a double key hole slot as indicated at 35-36-37, which will enable the handle to be hung from a nail, or analogous projection, either in a normal, inverted, or other position, dependent upon the disposition of the restricted slots 36-37 thereof.

95 The end of the short arm 31 is rotatably attached to the casing 10 in any suitable way, for the attainment of the desired ends, as for instance by a pivot pin 38 passing through aligning apertures in the end of the short arm 31 and in a spaced angle bar or cleat-like member 39 on the lamp casing, 100 the said pin having a head 40, located within the space between the bar 39 and the lamp casing 10, and at its other end being threaded to receive securing nuts 41. Thus the aforesaid handle is rotatably associated with the lamp casing, by means of the pivotal mounting of its short arm 31 at a position intermediately of the ends of its long arm 32, and may be adjusted and held firmly adjusted, at various angles relatively thereto, 115 as will be obvious. Also it may be stated that, although not strictly essential, the length of said handle element is preferably no greater than the length of the lamp casing, so that when disposed longitudinally of 120 the casing it will not project beyond the ends of the latter.

125 42 simply indicates a lip-like projection or support, on the face of the casing opposite to that side to which the handle is pivoted, such means being projected from the forward portion only, of the casing, to permit of the lamp being supported, in an inclined or tilting position, upon a flat surface or the like, and obviously this element 130

42 could be of a radially adjustable character to vary the degree of the tilting support of the lamp.

From the foregoing complete description, it is believed that the full objects, advantages and functioning of the invention will be clearly apparent, but, while there has thus been disclosed one embodiment thereof, it may later be found to be expedient or desirable to make some alterations, although without departing from the gist of the invention.

It is to be understood, therefore, that the invention is not to be restricted to all of the details exactly as illustrated, described and disclosed, excepting as they may come within the terms of the claims, or their equivalent, or as when fairly interpreted in the light of the specification if necessary.

20 What I do claim, as new and patentable, is:—

1. In combination with an elongated lamp casing, for a portable electric projector light having its lens element closing one end 25 of said casing, a unitarily combined handle and hanger support therefor, associated with the longitudinal wall of said casing, comprising a short arm forming an approxi-

mately U-shaped continuation of a substantially parallel longer arm that terminates in an open hook disposed towards the said short arm, and means so connecting said short arm to the longitudinal wall of said casing as to permit of the rotary adjustment of said unitarily combined support while at 35 all times otherwise maintaining the same against displacement.

2. In combination with an elongated lamp casing, for a portable electric projector light having its lens element closing one end of 40 said casing, a unitarily combined handle and hanger support therefor comprising a short arm forming an approximately U-shaped continuation of a substantially parallel longer arm that terminates in an open hook 45 disposed towards the said short arm, the said combined support being of no greater length than that of said casing, and means so connecting the end of said short arm to the longitudinal wall of said casing, at approximately a central position along the latter, as to permit of the rotary adjustment of said support while at all times otherwise maintaining the same against displacement.

In testimony whereof, I affix my signature.
ISAAC JONES.
